UNITED STATES PATENT OFFICE.

EMIL EK, OF PORTLAND, MAINE, ASSIGNOR TO ADDE AND COMPANY, OF PORTLAND, MAINE, A CORPORATION OF MAINE.

OPERATING DEVICE.

Application filed October 27, 1925. Serial No. 65,128.

This invention relates to improvements in operating devices. More especially it relates to an improved pawl and ratchet connection between two rotatable members, wherefore by one of them may turn through a variable range without causing the other member to be rotated beyond a predetermined amount. The invention is shown and described in its application to a counter wherein a tally wheel is turned a predetermined angular amount, by the movement of a pawl through a partial, or a complete rotation in one direction, while similar movements of the pawl in the reverse direction have no effect upon the wheel.

It is an object of the present invention to provide transfer mechanism which is adapted to be actuated by an oscillating or a rotating element. It is a feature of the mechanism that the degree of swing of an oscillating element or the travel of a reciprocating element may exceed the minimum movement required to actuate the transfer mechanism without affecting the predetermined operation of the latter. More specifically the invention is directed to the provision of a pawl which when rotated through either a partial or a complete rotation in one direction will effect a precise angular displacement of a ratchet wheel, and which when rotated in the opposite direction will produce no turning effect on the wheel whatever.

The best mode in which I have contemplated applying the principles of my invention is disclosed in the accompanying drawing, but this is to be considered as merely illustrative.

It is intended that the patent shall cover by suitable expression in the appended claims, whatever features of patentable novelty exist in the invention disclosed.

In the accompanying drawings,

Figure 1 is a plan of a counter, with cover removed, embodying the present invention;

Figure 2 is an elevation in section on line 2-2 of Figure 1;

Figure 3 is a plan showing the transfer mechanism separate from the counter;

Figure 4 is a perspective view of the pawl; and

Figure 5 is a view of a portion of the counter showing a crank connected to the main shaft.

Referring to the drawings, the counter

a main shaft 12, having connection with the machine or moving element (not shown) whose operations are to be counted, and a countershaft 14 carrying a series of the tally wheels 16. On the right side of each tally wheel is a gear wheel 18 having ten teeth, and on the left side is a transfer pawl 19 having one tooth 19'. These three elements are fastened together by pins 17, and are together rotatable on the fixed counter shaft 14. On the main shaft 12 is a series of back gears 20 each secured by pin 21 to the larger end of a conical hub 23. These gears with their attached hubs are separately rotatable on shaft 12 and are so proportioned and arranged that one back gear meshes with a gear wheel 18 on one tally wheel and with the single toothed transfer pawl of the tally wheel of next lowest order. Accordingly as any one tally wheel is turned through a complete rotation, its attached transfer pawl 19 turns the engaging back gear one tenth of a rotation and this movement of the latter advances the tally wheel of next higher order one unit at the same time. In the base of the casing is a series of detents or stop pins 32 arranged one for each back gear, whereby the rotative movement of the latter, and consequently the tally wheel with which it is engaged, is yieldingly limited to prevent any over-running.

The main shaft 12 may be connected directly with a rotating element, but in the counter illustrated it is intended that this shaft shall be merely oscillated, and accordingly a lever 22 is fixed thereon, having an offset 22^a which brings up against a boss 10^a on the casing, as the shaft and arm are urged clockwise by a spring 24 coiled about the main shaft with one end hooked to a suitable catch which may be the set screw 26 holding the collar 25 on the main shaft, and its other end hooked around the counter shaft.

The mechanism for effecting movement of the tally wheels comprises a ratchet wheel 34 attached to the unit tally wheel having ten teeth each one of which has a face 34^a which is radial and another face 34^b which is inclined to form a cam face. In the preferred form there is a hub 36 securely fastened to the main shaft, having a diametrical groove 36^a whose edges form bearing surfaces for a pawl 38. The latter has a central elongated slot 38^a through which

the main shaft 12 extends, and at one end of the slot there is a notch 38^b adapted to receive and hold a compression spring 40 which bottoms on a pin 40' on the hub. 5 This spring constantly urges the pawl along the groove transversely of the axis of the shaft, its effect being limited by the engagement of the central slot 38^a with the shaft. The hub is placed on the shaft against the 10 back gear of the unit tally wheel so that there may be no movement of the pawl along the shaft, the gear on one side and the hub on the other holding the pawl in its operative position directly opposite the ratchet wheel 34. The operative end of the pawl has its corners rounded to form cam faces, 38^c and 38^d between which is a notch 38^d adapted to receive a tooth of the ratchet wheel, when the notch 38^a and a tooth are 15 directly in line with the axes of the two shafts. Each tooth in turn will assume such a position because of the stop pin 32.

When the arm 22 is pulled counter-clockwise the main shaft is likewise turned and 20 with it the hub 36 and pawl 38. The lower side of the notch 38^d in the end of the pawl engages the radial face 34^a of the ratchet tooth and turns the latter one tenth of a rotation. When this has occurred, the pawl 25 end and tooth will have moved far enough in their respective circular paths to separate. The ratchet will be arrested by the stop pin before mentioned, but the pawl can continue to rotate as far as the arm may be turned. 30 If the main shaft is to be fully rotated, the arm 22, spring 24 and set screw collar 25 are removed and a crank 22' attached to the main shaft 12, a spacing collar 23 being also 35 added to properly position the crank as shown in Figure 5. With the pawl rotating its leading cam face 38^c will ride on the sharp edge of the tooth, then in line with the axes, causing the pawl to be retracted against its spring 40 until the notch 38^d 40 comes opposite the tooth, whereupon the spring 40 will snap the pawl toward the ratchet to bring the lower wall of the notch again in operative contact with the radial face of the tooth.

45 As illustrated in Fig. 1, the arm and main shaft make only a partial rotation, being returned to their initial position under the influence of the spring 24 with the lug 22^a against the boss 10^a. In this reverse movement of the pawl, the lower cam face 38^c rides on the top of the ratchet tooth retracting the pawl as before explained, until the notch is opposite the tooth. When this occurs, the pawl will snap into engagement 50 with the tooth and if the arm be then turned in the counterclockwise direction, the pawl will again advance the ratchet one tenth, as before. Thus the cycle can be indefinitely 55 repeated and the operations of machine or moving element counted. It is to be noted

that in case the reverse movement of the pawl continues beyond the position shown in Figure 2 the ratchet wheel will not be turned however, because the end of the upper cam face 38^c sliding on the inclined face 34^b of the tooth will cause the pawl to retract enough to pass by the tooth. Thus the movements of the pawl will only be effective to turn the ratchet wheel when the pawl is moving counterclockwise. 75

Although particularly shown and described in connection with a counter, the use of an operating device embodying the present invention is not so limited, but can be employed for turning a counter-shaft intermittently, in step-by-step movements, in consequence of either a rotatory or oscillatory turning of a main shaft. When applied in a counter, the latter becomes at once adapted for registering rotations or oscillations of an actuating element, when moving in the operative direction. 80

I claim:

1. The combination with a main shaft and a counter shaft having a ratchet wheel carried thereon, of a pawl mounted on said main shaft and rotatable therewith; said main shaft having a bearing surface transverse to its axis along which said pawl is adapted to slide into engagement with said wheel; said pawl having a central slot through which the shaft passes; and means interposed between said shaft and one end of the slot for urging the pawl toward wheel engaging position. 90

2. A counter comprising, in combination, a main shaft; a counter shaft carrying a ratchet wheel; a pawl mounted on said main shaft, rotatable therewith and adapted for transverse movement thereof to engage said wheel; and spring means urging said pawl toward wheel engaging position; said pawl having a notch at one end for securing a tooth of the wheel, whereby the wheel is turned upon rotatory movement of the pawl. 100

3. A counter comprising, in combination, a main shaft; a counter shaft carrying a ratchet wheel; a pawl mounted on said main shaft, rotatable therewith and adapted for transverse movement thereof to engage said wheel; and spring means urging said pawl toward wheel engaging position; said pawl having a cam face at one end whereby upon engagement with a tooth on the wheel the pawl is retracted against said spring means, 110 to permit the pawl to slide along said tooth, there being a notch adjacent to said cam face into which the tooth is received upon movement of the face past the tooth, so that the engagement of a side of said notch and the tooth will cause the wheel to be turned upon further rotatory movement of the pawl. 115

4. A counter comprising, in combination, a main shaft; a counter shaft carrying a ratchet wheel; a pawl mounted on said main 120

shaft, rotatable therewith and adapted for transverse movement thereof to engage said wheel; and spring means urging said pawl toward wheel engaging position; said pawl having at one end a pair of cam faces with a notch between them; the said faces upon engagement with a tooth on the wheel causing said pawl to be retracted against said spring means, and the notch permitting the spring means to move the pawl toward said wheel to engage said tooth; the said tooth

having a cam face adapted to coact with one side of the notch to retract the pawl when turned in one direction, and having a radial face adapted upon engagement with the other side of the slot to cause the wheel to be turned with the pawl. ¹⁵

In testimony whereof I hereunto affix my signature at Portland, Maine, this 13th day of October, 1925.

EMIL EK.
